UNITED STATES PATENT OFFICE.

HERMAN S. HEICHERT, OF PITTSBURGH, PENNSYLVANIA, ASSIGNOR TO PITTSBURGH PLATE GLASS COMPANY, A CORPORATION OF PENNSYLVANIA.

APPARATUS FOR CLEANING PLATE-GLASS POLISHING RUNNERS.

Application filed March 23, 1923, Serial No. 627,083. Renewed March 31, 1926.

The invention relates to apparatus for polishing plate glass, and particularly to that form of apparatus in which the glass to be polished is carried beneath a series of 5 polishers on cars or other carrier apparatus. After a certain period of use, the felts of the runners become caked with rouge or other polishing material, and their efficiency is reduced. The principal object 10 of the present invention is to provide a simple, convenient arrangement, for washing the felts of the various machines at intervals without interfering with the continuous operation of the apparatus and without 15 interfering with the efficiency of the polishing machine adjacent the one which is being washed.

In its preferred form, the apparatus comprises a series of frames extending transversely of the tables or carriers and provided at their lower ends with scrapers or squeegees, together with means for applying water to wash the machines. These 20 scraper devices are preferably mounted for 25 swinging movement so that when not in use, they are moved to a position out of contact with the glass and held in such position. The water for washing may be applied from spray pipes carried by the swinging frames or may be applied to each machine from a hose or other suitable supply 30 means. It is preferred to use a scraper or equivalent shielding means between every pair of tables, but this is not an essential as 35 the scraper or shielding means may be made portable and moved from machine to machine, in which case the number of such devices required is reduced to a minimum, although the convenience in use is not as 40 great as in the preferred apparatus. Certain embodiments of the invention are illustrated in the accompanying drawings wherein—

Figure 1 is a horizontal section taken on 45 the line I—I of Fig. 3. Fig. 2 is a side elevation. Fig. 3 is an end elevation. Fig. 4 is an enlarged sectional detail view. Fig. 5 is an enlarged sectional detail view showing a modified form of shield or scraper. 50 And Fig. 6 is a detail section showing another modification.

Referring to the drawings, 1—1—1 are a series of tables mounted upon the track 2 and carrying a series of sheets of glass 3 55 placed end to end which are to be polished.

Arranged in series above the tables are a series of polishing machines, two of which are illustrated in Figs. 1 and 2. These polishing machines comprise a supporting framework 4, made up of commercial sections, as illustrated, and carrying rotating frames 5 upon which the polishing runners 6 are carried. The runners carry the polishing felts 7 upon their lower sides and are mounted in spindles 8 slidably vertically 60 through the frames 5, so that the weight of the runners is imposed upon the glass when the supporting frames are lowered. The frames 4 are rotated by means of spindles 9 provided with the spur gears 10 and 65 driven from pinions 11. Each machine preferably has its own operating motor 12 mounted upon the top of the framework and arranged to drive the spindle 9 through the belt 13 and gears 14 and 15, the latter 70 of which is keyed to the shaft 16 which carries the pinion 11. The method of driving the spindle 9 is immaterial in so far as the present invention is concerned.

Provision is made for raising and lowering the runner frames 5 by means of the lever 17 pivoted upon the bracket 18 and engaging the thrust bearing 19, the upper half of which is secured to the shaft 9. The outer end of the lever is provided with the 80 threaded rod 20 which is moved up and down through the nut 21, carried upon the bracket 22 by means of the wheel 23. Along each side of the track 2 is a wall 24, upon which wall is mounted the shielding 85 or scraping devices for the glass and also the spray pipes. Extending transversely between the various machines are a series of pipes 25 mounted at their ends in the bearings 26 mounted upon the top of the 90 wall 24. Extending downwardly from the pipe 25 is a sheet metal plate 27 carrying at its lower end the spray pipe 28. This plate also carries a transversely extending bar 29 which is slotted upon its lower side 100 and carries the rubber plates 30 for engaging the surface of the glass. The pipe 25 carries at its end a valve casing 31 (Fig. 1) which communicates with the pipe 32 leading into the spray pipe 28. This casing is 105 provided with a valve operated from the handle 33 and provided with the inlet pipe 34 which is connected to a source of water supply. The spray pipe 28 is provided with a series of perforations directed down- 110

wardly and laterally, as indicated in Fig. 4, whereby a supply of water is provided for washing the glass and the polishing felts engaging the glass in advance of the spray 5 pipe.

- In order to hold the scrapers or squeegees yieldingly against the glass, the pipes 25 are provided at their ends with suitable arms 35 carrying the counterweights 36. 10 When a machine is being washed, the scrapers on each side occupy the position indicated in Figs. 2 and 4, while all the rest of the scraping devices are in inoperative position, the arms 35 being swung to the right 15 until the weights rest upon the top of the wall 24 or come in contact with suitable stops. This lifts the scrapers or squeegees out of contact with the glass and maintains them in inoperative position until they are 20 again required for use.

In using the washing system, preferably the felts on only one machine are washed at a time, so that the main portion of the system remains in efficient operation. The 25 plates 27 in conjunction with the squeegees 30 effectually seal off the machine being washed from adjacent machines so that the excess of water supplied during the washing operation, and which might otherwise 30 run along the table and wet the adjacent tables to such an extent as to reduce their efficiency, is prevented from so doing. This is particularly desirable on the side of the machine toward which the glass is moving 35 as the tendency is for the excess water to be carried in this direction, but there is also a considerable tendency of the water to move in the other direction and dilute the rouge mixture of the machine on such side, so 40 that it is desirable to have the scraping devices in position on both sides of the machine. This also permits the water to be applied much more freely than would otherwise be the case, so that the washing operation 45 may be concluded quickly and the time lost by the machine incident to the washing operation is reduced to a minimum.

When it is not desirable to supply the water to the glass by means of the transverse 50 pipes 28, the washing may also be effected in a somewhat simpler way in connection with the scraping device illustrated in Fig. 5. In this construction, there is no transverse spray pipe and the water is supplied 55 for washing purposes by means of a hose in the hands of an operator at the side of the machine. As here shown, the pipe 37, which acts as a shaft for the scraper device, is mounted at its end in notches cut in the angle iron 38 mounted upon the top of the wall 24. This pipe carries a rubber curtain 39 which extends around the pipe at its upper end and at its lower end is secured to a pair of transverse plates 40 which carry the 60 scraper 41 between them. The parts 39, 40

and 41 are secured together by means of the bolts 42 which also extend through stiffening arms 43 which encircle the pipe 37 at their upper ends. The pipe 37 carries at one end, or at each end, an arm 46 provided 70 with a counterweight 47 which parts perform the functions of the arms and weights 85 and 36 of the Fig. 4 construction. In one position the scrapers are held against the glass as indicated in the drawing and in the 75 other position these members are held up out of contact with the glass. This simplified form of scraper device may be employed between all the various polishing machines 80 at the same time, as in the Fig. 1 construction, or the system may be operated with only two of these devices which are moved from one position to another in order to carry out the successive washing operations. The mounting of the pipes 37 in the notches 85 of the angle irons 38 facilitates this method of shifting from one position to another as it is a simple matter to lift the pipe with the parts carried thereby and remove it to a new 90 location.

Fig. 6 illustrates a modification in which the brush 48 performs the function of the scrapers of the apparatus as heretofore described. This brush is carried by a box or guard 49 and may be moved up and down by suitable screw devices 50 to vary the pressure of the brush upon the glass. The casing or guard 49 is supported at its ends upon the wall 24 and may be moved from place to place in the same manner as the device of 95 Fig. 5. The casing 49 in this construction also preferably carries the transverse spray pipe 51 to which water is supplied by any suitable means. The brush may be geared up to a suitable motor, not shown, and 100 driven at a speed which is best suited to meet requirements, the direction of rotation being such as to carry the water back toward the machine which is being washed. In order to take care of any water which is carried around by the brush to the right hand side thereof, a guard 52 is provided so that 105 the water carried over collects in the groove 53 which leads laterally through the side of the casing to a suitable outlet.

What I claim is:

1. In combination in apparatus for polishing plate glass, a series of polishing machines, each having a rotatable frame provided with a set of polishing runners, means for carrying the glass to be polished beneath the runners of the series of machines, means for applying water to the machines to wash out the polishing material from the runners, fixed supporting means along the line of travel of the means carrying the glass on each side thereof, and shields between the machines extending across the glass to prevent the water employed in washing one machine from passing to the next machine,

- said shields being mounted upon said supporting means for vertical movement so that they may be moved out of contact with the glass when the washing operation is not in progress.
2. In combination in apparatus for polishing plate glass, a series of polishing machines, each having a rotatable frame provided with a set of polishing runners, means for carrying the glass to be polished beneath the runners of the series of machines, means for applying water to the machines to wash out the polishing material from the runners, and shields between the machines extending across the glass to prevent the water employed in washing one machine from passing to the next machine, said shields being mounted for swinging movement such that they may be moved out of contact with the glass when the washing operation is not in progress.
3. In combination in apparatus for polishing plate glass, a series of polishing machines, each having a rotatable frame provided with a set of polishing runners, means for carrying the glass to be polished beneath the runners of the series of machines, means for applying water to the machines to wash out the polishing material from the runners, movable frames extending transversely between the various machines, scrapers carried thereby for engaging the glass, spray pipes also carried by the frames, and means for supplying water thereto.
4. In combination in apparatus for polishing plate glass, a series of polishing machines, each having a rotatable frame provided with a set of polishing runners, means for carrying the glass to be polished beneath the runners of the series of machines, means for applying water to the machines to wash out the polishing material from the runners, a swinging frame extending transversely of the glass between the machines and provided with scrapers arranged in one position to yieldingly engage the glass and in another position to be out of contact therewith.
5. In combination in apparatus for polishing plate glass, a series of polishing machines, each having a rotatable frame provided with a set of polishing runners, means for carrying the glass to be polished beneath the runners of the series of machines, means for applying water to the machines to wash out the polishing material from the runners, swinging frames extending transversely of the glass between the machines and provided with scrapers, and counter-weight means for the frames arranged when in one position to cause the scrapers to engage the glass, and when in another position to hold the scrapers out of contact with the glass.

In testimony whereof, I have hereunto subscribed my name this 16th day of March, 1923.

H. S. HEICHERT.
